UNITED STATES PATENT OFFICE.

DANIEL P. KELLOGG, OF LOS ANGELES, CALIFORNIA, ASSIGNOR OF ONE-HALF TO
PATRICK SHEEDY, OF LOS ANGELES, CALIFORNIA.

CAR-ROOF.

1,230,720.

Specification of Letters Patent. Patented June 19, 1917.

Application filed July 14, 1916. Serial No. 103,211.

To all whom it may concern:

Be it known that I, DANIEL P. KELLOGG, a citizen of the United States, and a resident of the city of Los Angeles, county of 5 Los Angeles, and State of California, have invented a new and useful Improvement in Car-Roofs, of which the following is a specification.

This invention relates to freight car roofs, 10 and has for its object the production of a flexible waterproof roof made of fireproof or substantially fireproof materials. A further object of the invention is a continuous roof without seams or loose joints to open 15 up and leave crevices through it. A further object is a roof which can be repaired readily at any point on the line with stock materials.

Further objects of the invention appear 20 below in connection with the description of the forms of roof shown in the accompanying drawings. The invention consists in the use of a flexible support for the roof, and in the character of the roof and its manner of 25 attachment to the car, as hereinafter claimed. The details of the invention appear more fully in the following description of the embodiments thereof shown in the drawings.

The same reference characters are used in 30 the several views of the drawings to designate like parts.

Referring to the drawings,

Figure 1 is a plan view of an end portion of a car having a roof embodying the invention, parts of the roof being removed to disclose the construction of the parts beneath;

Fig. 2 is a vertical cross-section through the ridge portion of the roof, on the line 40 2-2 in Fig. 1;

Fig. 3 is a vertical cross-section through the eaves portion of the roof, on the line 3-3 in Fig. 1;

Fig. 4 is an underneath view of a portion 45 of the roof shown in Fig. 3, showing the construction near the end of a carline;

Fig. 5 is a cross-section of the same on the line 5-5 in Fig. 3;

Fig. 6 is a longitudinal section of the roof

at the end of the car, on the line 6-6 in 50 Fig. 1;

Fig. 7 is a cross-section at and near the eaves of a roof embodying a modified form of the invention;

Fig. 8 is a plan view of a portion of a roof 55 embodying another embodiment of the invention; and

Fig. 9 is a cross-section of the construction shown in Fig. 8 on the line 9-9 in Fig. 8.

The roof shown in Figs. 1 to 6, inclusive, 60 consists of a layer of tar paper 11 covering the entire car, and over which is a layer of wire mesh 12 embedded in a suitable waterproof roofing cement. A top coat 13 of suitable waterproof cement is put on over the 65 wire mesh layer. The waterproof roof thereby produced is secured in place by nailing the wire mesh before it is embedded in cement to spaced supports 14 which are loosely arranged on the carlines 15 and end 70 plates 16 of the car. The edges of the mesh are soldered or otherwise secured to metal eaves flashing strips 17 which are arranged around the top edges of the car. The outer edges 18 of the eaves flashing strips are 75 bent down and loosely hooked under angle strips 19 which are nailed to the sides and ends of the car just below the top. Sheathing boards 20 are arranged lengthwise of the car between the supports 14, leaving a slight 80 gap on each side of each support. The sheathing boards 20 may be nailed or otherwise secured on top of the carlines; and the supports 14 are prevented from rising up by angles or cleats 21 which are nailed to their 85 under sides one on each side of each carline. The cleats 21 are spaced from the carlines, and their ends project under the roof sheathing boards but are not secured thereto. The ends of the supports 14 are fastened to end 90 angles or cleats 22 which extend nearly from ridge to eaves on each side of the car.

The running boards 23 are nailed or otherwise fastened to spaced running board saddles 24 which fit astride of the ridge of 95 the roof and rest on the plastic roofing. The ends of the running board saddles are bolted to the middle pair of supports 14. This

construction permits the running boards, roof covering and supports to move as a whole relative to the roof sheathing boards, carlines and side and end plates.

5 In the modification shown in Fig. 7, a layer of canvas 25 is used instead of tar paper and wire mesh, and is covered by a layer of plastic cement or one or more coats of waterproof paint 26. The edges of the canvas 10 are turned under and hooked into the folded inner edge of the eaves flashing strip 27 to make a tight joint. The outer edge of the flashing strip is turned under and loosely hooked under the outwardly projecting 15 flange of the angle bar 28 which is secured to the side of the car along the eaves.

In the construction shown in Figs. 8 and 9, a sheet metal roof 29 is used instead of a composite roofing, the sheets being soldered 20 or welded together. The roof is held to the supports 14 by metal straps 30 which pass under the supports and are soldered or otherwise secured to the roof sheets.

It is apparent from the foregoing description that changes in the details of construction may be made without sacrificing the advantages of the invention, and the invention is not restricted to the precise details of construction shown and described, or any of 30 them.

I claim the following as my invention:

1. A car roof having a roof substructure forming part of the frame of the car, a continuous waterproof covering for said substructure extending from side to side and from end to end of the car, rigid supporting means for said covering secured to its under side, said supporting means spanning openings in said substructure and sufficient of 35 said supporting means being fastened together independently of said substructure and loosely secured thereto to stiffen said roof covering and to permit limited freedom of movement of said roof covering with 40 respect to said car.

2. A car roof having a continuous waterproof covering of plastic material extending from side to side and from end to end of the car, stiffeners for said covering comprising separately movable supporting and fastening means extending beneath and secured to its under side, said supporting and fastening means on either side of the ridge being connected together and having limited 55 freedom of movement with respect to said car.

3. A car roof having a continuous waterproof covering extending from side to side and from end to end of the car, a supporting frame for the middle portions of said covering, said supporting frame having limited freedom of movement with respect to said car, and eaves flashing strips loosely engaging the car at the eaves for movement rela-

tively thereto, said roof covering being fastened to said eaves strips at its edges and to said supporting frame between its edges whereby it is securely held in place throughout the length and width of the car. 65

4. A car roof comprising a plurality of spaced supports extending lengthwise of the car, a continuous roof secured upon said supports, means for connecting said supports and for movably securing said supports to the car, and means for loosely securing the edges of said roof at the sides and ends of the car. 70

5. A car roof comprising a plurality of spaced supports extending lengthwise of the car, a continuous roof secured upon said supports, running board supports bolted to said supports, means for movably securing said supports to the car and means for loosely securing the edges of said roof at the sides and ends of the car. 75

6. A car roof comprising a plurality of spaced supports extending lengthwise of the car, a continuous roof secured upon said supports, supporting sheathing arranged between and spaced from said supports, and means for movably securing said supports to the car. 80

7. A car roof comprising a plurality of spaced supports extending lengthwise of the car, a continuous flexible roof rigidly secured upon said supports, supporting sheathing arranged between and spaced from said supports, and means for movably securing said supports to the car. 85

8. A car roof comprising a plurality of spaced supports extending lengthwise of the car, a continuous flexible roof rigidly secured upon said supports, supporting sheathing arranged between and spaced from said supports, and means for movably securing said supports to the car, the eaves edges of 100 said roof being stiffened with metal and loosely secured to the car. 105

9. A car roof comprising a plurality of spaced supports extending lengthwise of the car, the supports on each side of the ridge being secured together by cross-pieces pivoted thereto, a continuous roof secured upon said supports, means for movably securing said supports to the car, and stops for limiting the endwise movement of said supports. 110

10. A car roof comprising a plurality of spaced supports extending lengthwise of the car, a continuous roof secured upon said supports, supporting sheathing arranged between and spaced from said supports, and means for movably securing said supports to the car, said means comprising cross cleats fastened to the under side of said supports and projecting under the adjacent 120 sheathing. 125

11. A roof supporting frame comprising carlines, purlins extending lengthwise of the

car over the carlines, said purlins being movable lengthwise of the carlines, and roof sheathing supported on said carlines between said purlins.

5 12. A roof supporting frame comprising carlines, purlins extending lengthwise of the car over the carlines, said purlins being

movable transversely of the carlines, and roof sheathing supported on said carlines between said purlins and spaced therefrom. 10

Signed at Los Angeles, Cal., this 5th day of July, 1916.

DANIEL P. KELLOGG.
